UNITED STATES PATENT OFFICE.

WILLIAM CARPENTER WRIGHT, OF PADUCAH, KENTUCKY, ASSIGNOR OF ONE-HALF TO
FINIS EWING LACK, OF PADUCAH, KENTUCKY.

MACHINE FOR UNITING KNIT FABRICS.

1,092,885.

Specification of Letters Patent. Patented Apr. 14, 1914.

Application filed September 4, 1912. Serial No. 718,472.

To all whom it may concern:

Be it known that I, WILLIAM C. WRIGHT, a citizen of the United States, residing at Paducah, in the county of McCracken and State of Kentucky, have invented certain new and useful Improvements in Machines for Unitting Knit Fabrics, of which the following is a specification.

My invention relates to improvements in machines for uniting knit fabrics, the machine being adapted to unite or connect the meeting edges of two pieces or portions of knit fabric by joining the loops of the adjacent edges thereof by means of an elastic seam or chain of stitches as in the production of hosiery, underwear, and the like.

The present embodiment of the invention is particularly designed for closing the usual opening in the toe portion of the knitted stocking, and is designed to form an elastic chain of stitches for joining the adjacent loops of the two portions of the fabric to be united, said elastic chain or seam being formed transversely in the toe portion of the stocking and being adapted to coöperate with the loops of the stocking fabric to provide transverse elasticity in this portion of the stocking.

The present invention is particularly designed and adapted for use in connection with machines of the general character disclosed in my application for Letters Patent for improvements in machines for uniting knit fabrics, filed April 16th, 1912, Serial No. 691,179, the present improvements relating particularly to an improved form of looper hook and mechanism for operating the same.

In order to provide the necessary or required elasticity in the uniting seam or chain of stitches, a stitch finger is mounted above and extends in the direction of the travel of the ring of impaling pins in coöoperative relation with the thread needle and thread carrying looper in the stitch forming operation, said stitch finger being adapted to be included in a chain of uniformly formed stitches, the latter being withdrawn or shed off from the outer or free end of the stitch finger by the progressive movement of the united loops on the subjacent impaling pins, thus providing a uniformly formed elastic chain of stitches.

The improved form of looper hook to which this application particularly relates

is rotatably mounted above and at an angle to the plane of the ring of impaling pins being preferably mounted on the dial support opposite the feed side of the sewing mechanism, thus affording free or unobstructed access to the latter, as in threading the thread carrying parts, the improved looper hook being adapted to describe a substantially semi-circular path over and about said stitch finger and thread needle and to be stopped on opposite sides of the same in the sewing or looping operation, said looper hook when on one side or position, being adapted to advance and enter and take up the thread loop from the thread needle and after passing over the stitch finger and after the thread needle is in its rearward or receded position being stopped or held in proper position whereby the thread needle as advanced will enter and take up the loop from the looper hook, after which the latter will be returned to its initial or former position.

With the above mentioned ends in view, the invention consists in the novel construction, arrangement, and combination of parts, hereinafter described, illustrated in one of its embodiments in the accompanying drawings; and particularly pointed out in the appended claims.

Referring to the drawings, forming a part of this specification, Figure 1, is a top plan view of a machine constructed in accordance with my invention. Fig. 2, a side elevation of the same. Fig. 3, a perspective view of the sewing mechanism taken from the front or feed side thereof, the improved thread carrying looper hook being in its forward or advanced position, and the thread needle being about to advance and enter and take up the loop from the looper hook. Fig. 4, a similar view showing the thread needle advancing and the looper hook retreating to its initial position or the position opposite that shown in Fig. 3. Fig. 5, an enlarged view of the rotary looper hook actuating or operating mechanism, the cap or cover for the supporting block or bracket being removed for the purpose of clearer illustration of the parts. Fig. 6, a cross sectional view of the supporting block or bracket carrying the improved rotary looper hook, the latter being shown in its advanced position corresponding to the position shown in Fig. 3.

Similar numerals of reference designate

like parts throughout all the figures of the drawings.

The improved machine comprises a stationary bed plate 1, provided with an upwardly and outwardly projecting supporting arm 2. The arm 2, terminates in a bearing head 2^a, carrying a vertical shaft 3, and a stationary supporting disk or dial plate 4. The stationary support or dial plate 4, may 10 be provided with the usual ring 5, carrying a peripheral series of outwardly extending impaling pins 6. The loops of fabric to be united are placed over the impaling pins 6, in a well-known and understood manner, 15 and the ring of impaling pins, in the present instance, is given a continuous and uniformly revolving movement by means of suitable driving mechanism comprising a driving shaft A, mounted in a movable shaft 20 carrying arm B, said shaft A, receiving its motion by means of a bevel gear C, meshing with a bevel gear D, on the main driving shaft 7, the outer or free end of the driving shaft A, being provided with a worm gear 25 E, normally meshing with a gear wheel F, carried upon a shaft G, mounted beneath the dial plate 4, said shaft G, being provided at one end with a pinion H, meshing with a rack on the under side of the ring 5, carrying 30 the impaling pins 6. The driving shaft 7, is adapted to receive its motion by means of a suitable pulley 8, adapted to carry a suitable belting communicating with a suitable source of power, and pulley clutch 35 mechanism 9.

As a means for actuating the various parts or members comprised in the stitch forming mechanism, the driving shaft 7, may be provided with a crank disk or head 40 10, and the curved thread needle 11, is carried by and reciprocated over and above each of the impaling-pins by means of an oscillating needle arm 12, carried upon a bearing shaft or stem 13, extending from 45 the side of the supporting arm 2, of the machine. The oscillating needle arm 12, is adapted to be reciprocated by means of a pitman or connecting arm 14, connected at one end by means of a suitable coupling or 50 connection 15, and at the other by means of a suitable universal coupling or connection 16, the latter preferably comprising a suitable bearing screw 16, mounted in the crank disk or head 10, of the driving shaft 7, said 55 bearing screw passing through a pair of semi-spherical shaped members 17 (more fully shown and described in my said application, Serial No. 691,179) loosely fitted on the bearing member 16, and having their 60 convex sides extending toward each other and set in the bearing opening 18, of the pitman arm 14.

The needle arm 12, is provided at its upper portion with two bearing heads 12^a, 65 on the bearing shaft or stem 13, and said

bearing heads 12^a, are adapted to be moved longitudinally on said shaft or stem 13, whereby said needle arm 12, and thread needle 11, are moved laterally during both their to and fro reciprocation, by means of a wiper arm 19, pivotally connected at one end to the pitman or link member 14, and provided with a slotted bearing head 19^a, mounted on the shaft or stem 13, and interposed between the stationary standard 20, and the adjacent bearing head 12^a, the side of said bearing head 19, adjacent to the bearing head 12^a, having an inclined bearing portion or cam face 19^b, said inclined bearing portion 19^b, being adapted to move the 70 needle arm 12, laterally against the resistance of a spring 21, (see Fig. 1) as the curved thread needle 11, is reciprocated forwardly and through the loops of fabric to be united in the stitch forming operation, 75 and it will be observed that as said needle arm 12, and curved thread needle 11, are moved rearwardly, the bearing heads 12^a, of the needle arm will be returned to their former position as the bearing head 19^a, is 80 returned to its initial position, as particularly illustrated in Figs. 2 and 3, of the drawings. By reason of this movement, it is obvious that as the needle arm 12, is reciprocated it will be moved laterally in its 85 to and fro movements and thus carry the thread needle laterally while in the loops of fabric to correspond with the movement of the impaling-pins carried by the continuously rotating ring. 90

A stitch carrying guide member or stitch finger 22, is pivotally mounted in a supporting bracket 23, at one side of the ring of impaling-pins, the free end of said stitch finger being provided with a slightly depressed pointed or tapered tongue portion 22^a, said tapered tongue portion 22^a, being adapted to ride upon a plurality of the subjacent pins when the latter are empty and to ride or travel upon a plurality of the adjacent loops of the fabric to be united as the latter are carried under the tongue portion of the stitch finger by the impaling-pins. The depressed tongue portion 22^a, of the stitch finger is held down by the action of a spring 105 24, extending from the supporting bracket 23, the depressed tongue portion 22^a, of the stitch finger terminating in an offset portion 22^b, the curved thread needle 11, being adapted to pass at the rear of and in close proximity to the offset portion 22^b, during its reciprocatory movements through the loops of fabric to be united and over and above the subjacent impaling-pins carrying the loops to be united by the stitch forming 110 115 120 125 operation.

The improved thread carrying looper 25, is provided with a looper hook or head member 25^a, extending at an angle to the shank portion, said hook or head member 25^a, being 130

slightly curved on its inner side as at 25^b, to receive the thread needle and to form the loop 26, of the looper thread when the looper is in its forward position and the thread 5 needle is advancing to take up the loop 26, of the looper, as shown in Fig. 3 of the drawings.

As a means for rotatably mounting the improved looper 25, and giving the improved looper hook a substantially semi-circular to and fro movement or path and over and above the offset portion 22^b, of the stitch finger 22, as well as causing the looper hook to be momentarily stopped on 10 opposite sides of the stitch finger 22, as well as on opposite sides of the path of the curved thread needle 11, whereby the improved looper hook 25^a, is adapted to take up the thread from the thread needle when the latter is in its forward position under the offset portion 22^b, of the stitch finger and is about to retreat and whereby when the looper hook is in its forward position and has passed over the offset portion 22^b, and 15 the thread needle is in its rearward position and is about to pass forward to take up the loop 26, from the looper hook 25^a, as shown in Fig. 3 of the drawings, the improved looper is rotatably mounted with 20 its axis extending at an angle to the plane of the ring of impaling pins, in the present instance, by means of an axle shaft or stem 25^c, removably and adjustably mounted in a stub shaft 27, carried in a bearing or supporting block or member 28, the latter, in the present instance, being mounted on a bracket arm 29, mounted on the dial plate 4, and extending over and above the ring of impaling pins 6.

40 As a means for rotating or oscillating the thread carrying looper 25, in proper co-operative relation to the stitch finger and thread needle as above described, the stub shaft 27, in the present instance, is provided with a head or disk member 27^a, carrying an anti-friction roller or disk member 30, adapted to extend into and receive its motion from a curved guide-way or slot 31^a, of a reciprocatory plate or slide member 31, 45 slidably mounted in a guide-way 28^a, formed on one side of the supporting block or bearing member 28, said plate or slide member 31, being adapted to receive the requisite reciprocatory movement through the medium of a connecting link 32, the latter being detachably secured at one end to the end of the plate or member 31, by means of a bearing pin or lug 33, and at the other being adjustably and movably connected to a yoke 50 member 34, by means of an adjustably connecting bolt 35, said yoke member 34, being mounted upon an eccentric head or disk member 36, carried upon the main driving shaft 7. The stub shaft 27, carrying the looper 25, and the reciprocatory member 31,

in the present instance, are removably mounted in the bearing or supporting block 28, by means of a cap or cover 37, and the thread carrying looper 25, may be readily adjusted in the stub shaft 27, by means of a set screw 38, as shown most clearly in Fig. 6, of the drawings.

By reason of the above construction it will be seen that the improved form of rotatably mounted thread carrying looper is given the requisite movements in the stitch or looper forming operation by exceedingly simple and efficient actuating mechanism, and that the parts may be readily adjusted to meet the varying demands of actual service, the needle and looper moving in paths on opposite sides respectively of the offset or shoulder portion 22^b, of the stitch finger, the initial or first stitch being formed over and about said shoulder whereby said shoulder forms the zone of formation and the said tapered tongue portion 22^a, provides the zone of retreat for the stitches.

From the foregoing description, taken in connection with the accompanying drawings, the operation and advantages of my invention will be readily understood.

Having thus described one of the embodiments of my invention, what I claim and desire to secure by Letters Patent is,—

1. In a looping machine, a rotatably mounted looper hook, a thread needle, and means for reciprocating said looper hook and thread needle whereby said looper hook will be moved in a semi-circular path above the path of travel of said thread needle and will be stopped and caused to dwell in reversed substantially vertical positions on opposite sides of said thread needle, said looper hook in one position being adapted to take up the thread from the thread needle and in the other being adapted to have the thread needle take up the thread from the looper hook.

2. A looper hook actuating device, comprising a supporting block, a looper carrying shaft rotatably mounted therein and provided with an eccentric member, a reciprocatory member having a curved guide slot taking over said eccentric member whereby to oscillate said looper carrying shaft and cause the latter to dwell at the ends of the throw of said eccentric member, and means for actuating said reciprocatory member.

3. In a machine for uniting knit fabrics, a rotatably mounted looper hook, a reciprocatory thread needle, a stitch finger, and means for reciprocating said looper hook and thread needle in co-operative relation to said stitch finger, said looper hook being mounted to have a half somersault motion over said stitch finger and the path of travel of said thread needle and to be stopped in reversed substantially vertical positions on opposite sides of the latter.

4. In a machine for uniting knit fabrics, a rotatably mounted looper hook, a reciprocatory needle arm carrying a curved thread needle, a stitch finger mounted above and below the paths of travel of said looper hook and thread needle, respectively, and means for actuating said parts in coöperative relation to each other and causing said looper hook to be moved to and fro above and below the paths of travel of said curved thread needle.
5. In a machine for uniting knit fabrics, a looper hook provided with an axle shaft, a reciprocatory thread needle, and means for mounting and actuating said axle shaft whereby said looper hook is moved diagonally over and stopped to dwell in reversed vertical positions at opposite sides of the path of travel of said curved thread needle.
- 10 6. In a machine for uniting knit fabrics, a ring of impaling pins, a reciprocatory needle arm provided with a curved thread needle, means for actuating said ring of impaling pins and reciprocatory needle arm, a stitch finger mounted above the path of travel of said ring of impaling pins and said thread needle, a rotary looper carrying shaft, a looper mounted in coöperative relation to said stitch finger and thread needle, means for supporting said looper carrying shaft, and means for actuating the latter, whereby said looper is caused to assume and dwell in substantially vertical but reversed positions on opposite sides of the path of travel of said curved thread needle.
- 15 7. In a machine for uniting knit fabrics, a ring of impaling pins, a driving shaft, means for actuating said ring of impaling pins from said driving shaft, a reciprocatory needle arm operatively connected to said driving shaft, a stitch finger extending above the path of travel of said ring of impaling pins, a curved thread needle carried by said needle arm and adapted to pass above each of said impaling pins and below said stitch finger, a rotatably mounted looper hook, means for supporting said looper hook, and means for actuating said looper hook in coöperative relation to said curved thread needle and stitch finger, whereby said looper is caused to assume and dwell in substantially vertical but reversed positions on opposite sides of the path of travel of said curved thread needle.
- 20 8. In a machine for uniting knit fabrics, a thread carrying looper provided at one end with an axle stem and at the other with a looper hook, a reciprocatory thread needle, and means for actuating said thread needle and axle stem whereby said looper hook will be moved in a circular path above said thread needle and will be stopped and caused to dwell in reversed up and down vertical positions on opposite sides of the latter, said looper hook advancing and taking up the thread from the thread needle when the latter is in its advanced position and when said thread needle is in its rearward position said looper hook being stopped on the side of the path of the thread needle whereby the latter as advanced will enter and take up the loop from the looper hook.
- 25 9. In a machine for uniting knit fabrics, a ring of impaling pins, a reciprocatory needle arm provided with a curved thread needle, means for actuating said ring of impaling pins and reciprocatory needle arm, a stitch finger mounted above the path of travel of said ring of impaling pins and said thread needle, a rotary looper carrying shaft, a looper mounted in coöperative relation to said stitch finger and thread needle, means for supporting said looper carrying shaft, and means for actuating the latter, whereby said looper is caused to assume and dwell in substantially vertical but reversed positions on opposite sides of the path of travel of said curved thread needle.
- 30 10. In a machine for uniting knit fabrics, a ring of impaling pins, a driving shaft, means for actuating said ring of impaling pins from said driving shaft, a reciprocatory needle arm operatively connected to said driving shaft, a stitch finger extending above the path of travel of said ring of impaling pins, a curved thread needle carried by said needle arm and adapted to pass above each of said impaling pins and below said stitch finger, a rotatably mounted looper hook, means for supporting said looper hook, and means for actuating said looper hook in coöperative relation to said curved thread needle and stitch finger, whereby said looper is caused to assume and dwell in substantially vertical but reversed positions on opposite sides of the path of travel of said curved thread needle.
- 35 11. In a machine for uniting knit fabrics, a ring of impaling pins, a reciprocatory needle arm provided with a curved thread needle, means for actuating said ring of impaling pins and reciprocatory needle arm, a stitch finger mounted above the path of travel of said ring of impaling pins and said thread needle, a rotary looper carrying shaft, a looper mounted in coöperative relation to said stitch finger and thread needle, means for supporting said looper carrying shaft, and means for actuating the latter, whereby said looper is caused to assume and dwell in substantially vertical but reversed positions on opposite sides of the path of travel of said curved thread needle.
- 40 12. In a machine for uniting knit fabrics, a ring of impaling pins, a driving shaft, means for actuating said ring of impaling pins from said driving shaft, a reciprocatory needle arm operatively connected to said driving shaft, a stitch finger extending above the path of travel of said ring of impaling pins, a curved thread needle carried by said needle arm and adapted to pass above each of said impaling pins and below said stitch finger, a rotatably mounted looper hook, means for supporting said looper hook, and means for actuating said looper hook in coöperative relation to said curved thread needle and stitch finger, whereby said looper is caused to assume and dwell in substantially vertical but reversed positions on opposite sides of the path of travel of said curved thread needle.

In testimony whereof I have affixed my signature in presence of two witnesses.

WILLIAM CARPENTER WRIGHT.
